CIRCUIT CONTROLLER

Homer P. Chandler, Mansfield, Ohio, assignor to
The Ohio Brass Company, Mansfield, Ohio, a
corporation of New Jersey

Application June 8, 1933, Serial No. 674,901

9 Claims. (Cl. 172—238)

My invention relates to control devices for electric motors.

One of the objects of my invention is to provide a device for controlling the current to the motor upon starting.

Another object is to provide means for supplying a small current to the motor field when not in use in order to keep the motor warm and dried out. This is particularly advantageous where the motor is employed in damp places, such as mines.

Another object is to provide means for preventing a dangerous rush of current through the motor when the motor is first energized.

A still further object of my invention is to provide means for maintaining the circuit closed under predetermined voltage conditions but permitting the circuit to the motor to be opened automatically when the line voltage drops below a predetermined amount.

Another object of my invention is to automatically open the circuit to the motor should the current operating the motor exceed a predetermined amount for a predetermined time.

A still further object of my invention is to permit the stopping of the motor from a point at a distance from the motor or the control device at will of an operator.

Further objects of my invention will be apparent to those skilled in the art as I disclose my invention herein.

My invention resides in the new and novel construction, combination, and relation of the various parts and circuits herein shown and described in the drawing and specification.

In the drawing—

Fig. 1 is a schematic arrangement of the essential parts and circuits.

Fig. 2 shows a view in elevation in partial section of my invention to show largely its manner of mounting within a casing and three positions of the switch which I employ.

Fig. 3 is a view of the magnetic holding device for maintaining the switch closed under normal conditions.

Fig. 4 is a sectional view on the line 4—4 of Fig. 3.

Fig. 5 is a sectional view on the line 5—5 of Fig. 1 showing the switch blade in its fully closed position.

Fig. 6 is a view in partial section taken on the line 6—6 of Fig. 2 and shows a method of mounting terminal and switch blade to the casing and method of manually operating the switch blade to its closed position.

Fig. 7 is a perspective view of an electro-thermally controlled switch.

In the preferred embodiment of my invention I provide a metal casing or retainer 1 which is shown more in detail in my Letters Patent 1,972,979 issued September 11, 1934.

Secured to the casing is an insulating support member 2 and upon which an insulating base member 3 is mounted. The support member 2 affords a space between the receptacle 4 and the base 3.

Mounted upon the base 3 are a plurality of terminals 4, 5, 6 and 7. Mounted upon the inner wall of the receptacle 4 is a terminal 8 with an interposed insulating block 9 which may be of wood or other insulating material.

Pivotedly mounted in the terminal member 4 is a knife blade 10 shown in its fully closed or "running" position in full lines, and in its partially closed or "starting" position and in its "off" position in broken lines.

My invention also includes a resistance element 11 which is included in the main circuit through the motor when the switch blade is in its starting position, but is fully cut out of circuit when the switch blade is in its running position.

My invention also includes a thermal switch 12 shown in Fig. 7 and comprises a U-shaped element 13 of bimetal connected with its free ends 14 and 15 which in turn are mounted on the base 3. Attached to the unsecured end of the U-shaped thermal element 13 is an insulating member 16 and to this insulating member 16 is secured a contact member 17.

Mounted upon the base 3 is a terminal member 18 provided with an adjusting screw 19 arranged to make and break contact with the member 17, depending upon the flow of current through the thermal element 13.

Secured to the blade 10 is a member 20 of magnetic material.

Mounted upon the base 3 is a coil 21 having end holes 22 secured to a core 23 arranged to act upon the member 20 when the switch is in its fully closed position to hold it in position while the coil 21 is energized to a predetermined amount.

The switch blade 10 is provided with one or more coil springs 24 constantly acting to move the switch blade to its off position.

As the switch blade is moved from its off position to its running position, it will have an intermediate or starting position where it will con-

tact with the terminals 5 and 6, but when the blade is in its running position it will contact with the terminals 5 and 7 but not with the terminal 6, as shown in Fig. 5.

5 The switch blade is pivotally secured to the terminal 4 and the pivotal shaft 25 provided with an insulating member 25' may be made sufficiently long to extend through the side wall of the receptacle 1 and is further insulated 10 therefrom by means of the insulating bushing 26 and the shaft 25 has its inner end secured to the blade 18 to move the blade from its off position to its running position when the handle 27 secured to the outer end of the shaft 25 is 15 manually operated.

The switch blade may be operated through a mechanism producing delayed action when the switch has reached its starting position and such operating mechanism is shown in my Letters Patent above referred to.

Having described the various elements aside from the conductors which form a part of my invention, I will now describe the various connections and operation of my invention.

25 The invention is provided with terminals 28 and 29 for connecting to source of power L and L' respectively. The terminal 28 is connected to the switch terminal 4 by the conductor 30 thus the terminal 4 is constantly charged when the device is connected to the source of power. When the switch is in its off position the terminal 8 will be energized and current will flow through the conductor 31, resistance 32, conductor 33, to the field F of the motor M and 30 then through the field F, conductor 34 and terminal 28 to the power line L'. This permits what I term a warming current to flow constantly through the field F when not in use, thus keeping it warm and dry and the resistance 35 40 is adjusted to give the proper amount of current based on the voltage of the source of power.

When the operator has moved the switch blade to the starting position the terminals 5 and 6 will be energized. Current will flow from the terminal 5 through the conductor 35, holding coil 21, conductors 36, 37, 33, field F, conductor 34, terminal 29 to L'. This will place the field F directly across the source of power 50 L—L' in series with the interposed holding coil 21, thus fully energizing the field in advance of the switch being fully closed.

55 Current will also flow from the terminal 6 through the conductor 38, resistance 11, conductors 39 and 40 to the armature A, then through the conductor 34 and terminal 29 to the source of power L'.

With the blade in the starting position the operator maintains the switch in the starting 60 position until he feels that the motor has picked up such speed as the current controlled by the resistance 11 will permit or if the starting mechanism referred to in the above Letters Patent is employed the operator of course is compelled to hold the switch in the starting position for a short interval of time before he is able to move it to the running position.

70 When the operator moves the switch blade to the running position the terminal 6 is rendered dead (see Fig. 5) and the terminal 7 is energized, while the terminal 5 remains energized. Current now flows from the line L through the terminal 28, conductor 30, terminal 4, blade 10, terminal 7, conductor 41, fuse 42 (if used), conductor 43, thermal switch 12, conductor 40,

armature A, conductor 34, terminal 29 to line L', thus placing the motor in fully running condition.

It will be noted that the main current to the motor will flow through the thermal switch 12 and so long as this current does not exceed a predetermined amount for a predetermined time the switch 12 will not change materially, but if the sustained current exceeds a predetermined value then the thermal switch 12 will be heated and the contact 17 will engage the adjustable contact 19 thus closing a circuit which will shunt the coil 21.

When the contact 17 engages the contact 19 the shunt about the coil 21 will comprise the 15 conductors 36, 44 and 45, terminal 18, contacts 19 and 17, conductors 46 and 47.

The engaging of the contacts 17 and 19 and short-circuiting of the coil 21 will deenergize the coil 21 and the blade 10 will be released and 20 the spring 24 will return the blade to its starting position.

If it is desired to open the switch at a point remote from the control device conductors 48 and 49 are provided which lead to the terminals 25 50 and 51 respectively and from these terminals leads 52 and 53 may be run wherever desired and connected to a switch 54 which when closed will shunt the coil 21 the same as is the case when the contacts 17 and 19 engage. 30

It will be evident to those skilled in the art that from the above disclosure it would be possible to modify my invention without departing from the scope thereof and therefore I do not wish to be limited other than by my claims. 35

I claim:—

1. The combination with an electric motor having a field winding and an armature, of a circuit controller operable to "off", "starting" and "running" positions adapted to supply electric power to the motor, the said controller having a switch blade movable to each of the said positions and having at least one contact for each position and selectively engageable by the switch blade, means for connecting the armature to a contact in the "running" position, a resistor and means for connecting the armature in series with the resistor and to a contact in the "starting" position, a second resistor and means for connecting the said field winding in series with the second resistor to a contact in the "off" position to energize the field winding below normal to warm the winding when the motor is inoperative and the armature deenergized. 55

2. The combination with an electric motor having a field winding and an armature, of a circuit controller movable to "off" and "running" positions to supply electric current to the armature and field winding, the controller being provided with at least one contact for each position and a switch blade movable into selective engagement with the contacts at will of an operator, a normally open and thermally controlled switch and means for connecting the motor armature and switch in series to a contact in the "running" position, electrically operated holding means to hold the blade in the "running" position and connected for energization by the current through the field winding when the blade is in the "running" position, means connecting the thermally controlled switch to the holding means, the said switch arranged to short circuit the holding means when the sustained current to the armature exceeds a predetermined value 75

to release the blade, means to return the blade to the "off" position when released, a resistor and means to connect the resistor and the field winding in series and to a contact in the "off" position to energize the winding below normal when the motor armature is deenergized.

3. The combination with an electric motor having an armature and a field winding, of a controller manually movable to "off" and "running" positions and automatically movable from the "running" to the "off" positions and to control electric power to the motor, the controller being provided with only one switch blade and at least one contact for each said positions and selectively engageable by the blade, a resistor and means to connect it successively "in" and "out" of series with the armature as the blade moves from the "off" to the "running" position, a second resistor, means to connect it to the field winding and to a contact in the "off" position to sub-energize the field winding to heat the same while the armature is deenergized and automatic and manually releasable holding means to hold the blade in the running position.

4. The combination with an electric motor having a field winding and an armature, of a circuit controller operable to "off" and "running" positions to supply the motor with electric power, the controller being provided with at least one contact for each said position and a switch blade arranged to selectively engage the contacts, a coil operated holding means arranged to releasably hold the blade in the "running" position and means to connect the coil to the field winding, means to return the blade to the "off" position when the holding means releases the blade, a resistance element and means to connect the resistance element to the field winding and to the "off" contact to energize the field winding below normal when the motor armature is deenergized.

5. The combination with an electric motor having a field winding and an armature, of a circuit controller operable to an "off" and to a "running" position to supply current to the motor, the controller having at least one contact for each position and switching means to selectively engage the contacts, holding means and means to connect the holding means to the field winding to operate the holding means by current through the field to releasably hold the switching means in the "running" position, thermally operated means connected to the holding means to effect the release of the switching means when the sustained current through the armature exceeds a predetermined value, manually operable means connected to the holding means to effect the release of the switching means at will of an operator, a resistor and means to connect the resistor in series with the field winding and to a contact in the "off" position to sub-energize the winding to maintain heat therein when the motor is inoperative.

6. An electric motor controller comprising a switch blade movable to "off", "on" and "intermediate" positions and at least one contact for each position and selectively engageable by the blade, an armature resistor connected to the "intermediate" contact, a field resistor connected to the "off" contact, the switch blade movable to cut either of the resistors out of circuit when the blade engages either of the other two contacts and to cut both resistors out of circuit

when the blade engages the "on" contact, electro-magnetic means to normally hold the blade in the "on" position and releasing the same when de-energized, a device for shunting the holding means and having a thermal operating element electrically connected to the "on" contact and operable to shunt the holding means only when the blade engages the "on" contact and the sustained current through the thermal element exceeds a predetermined value and means to return the blade to the "off" position when the holding means is shunted.

7. A circuit controller for a motor, comprising a switch blade operable manually in one direction and a plurality of contacts selectively engageable by the blade, spring means constantly urging the blade to engage one of the contacts and a field resistor connected in circuit and to the said contact, a second contact engaged by the blade, a holding coil connected to the said second contact and energized when the blade engages the second contact and arranged to hold the blade in engagement with a third contact, a thermo-statically controlled switch connected to and energized from the said third contact to shunt the holding coil when the sustained current through the thermal switch exceeds a predetermined value, a fourth contact to be engaged by the blade in moving from the first to the third contact and an armature resistance connected in circuit and to the said fourth contact and arranged to be cut out of circuit when the blade is in engagement with the third said contact and manually controlled means to shunt the holding coil to de-energize the same.

8. A motor controller, comprising a manually operated switch blade having "off", "starting" and "running" positions, a contact corresponding to each position and engageable by the blade, a holding coil to maintain the blade in its "running" position when the coil is energized to a predetermined degree, a thermo-statically controlled switch to effect the deenergization of the holding coil, an armature resistance to control the initial rush of current and connected in circuit with the contact corresponding to the "starting" position, a resistance connected in circuit with the contact corresponding to the "off" position, and a contact engaged by the blade in both the "starting" and "running" positions and connected to the holding coil to energize the coil while the blade is in the "starting" and "running" positions and to hold the blade in the "running" position until deenergized as above provided.

9. The combination with an electric motor having an armature and a field winding, of a controller manually movable to "off" and "running" positions and automatically movable from the "running" position to the "off" position and to control electric power to the motor, the controller being provided with only one switch blade and at least one contact for each said positions and selectively engageable by the blade, a resistor and means to connect it successively "in" and "out" of series with the armature as the blade moves from the "off" position to the "running" position, a second resistor, means to connect it to the field winding and to a contact in the "off" position to sub-energize the field winding to heat the same while the armature is deenergized.

HOMER P. CHANDLER.
